FORCED CIRCULATION WATER-COOLED FURNACE DOOR

Otwin J. Braun, Pittsburgh, Pa., assignee to Reliance Steel Products Company, McKeesport, Pa., a corporation of Pennsylvania

Filed Oct. 2, 1961, Ser. No. 142,371
2 Claims (Cl. 122—498)

This invention relates to a forced circulation water-cooled furnace door and, more particularly, to a furnace door having structural members which both strengthen and serve as fluid conduits to cool the door.

Open-hearth furnace doors are generally exposed to the intense heat of the furnace combustion zone, and to better withstand the high temperature exposure a refractory lining is positioned on the door inner face. It has been found necessary in order to prevent heat destruction of the lining to cool the door and its lining by circulating water between the metal portion of the door, which normally is provided with an integral reservoir, and the lining. Studs or tubes are embedded within the refractory material, and water is circulated through these tubes to and from the reservoir in the metal or main body portion of the door. These tubes are fastened to the door main body portion in such a manner that the tubes anchor the refractory lining onto the door inner face.

Heretofore, the refractory lined, water-cooled doors had a useful life which was seriously limited because of the inefficiency of the door cooling system. That is, the water contained within the main body portion and the tubes within the refractory lining rapidly become heated to an elevated temperature. Circulating this heated water between the jacket or reservoir and within the tubes failed to maintain the temperature of the refractory material and the door metal to the low level or degree required to eliminate the destruction of the materials comprising the door.

In my copending application Serial No. 142,276 for a Forced Circulation Water-Cooled Door, filed October 2, 1961, which is assigned to the assignee of the instant application, there is provided a plurality of tubes which lock the lining in position on a furnace door, and which form a part of a forced circulation water-cooling system. Water is introduced into the door under pressure, and a constant volume of cool water is forced through the door-cooling system. The water is continuously forced out of the door at a rate of flow which maintains the temperature of the water within a designed range. As a result of the forced circulation of water in the novel door cooling system, the service life of the door is prolonged for a period exceeding that of the prior art doors.

This invention utilizes the forced circulation principle for cooling a furnace door much the same as that disclosed and claimed in my above-cited copending application. The general nature of the open-hearth furnace door is well known to include an inner and an outer face which are in parallel spaced relationship. The marginal portions of both door faces are flanged, with the inner face flange being turned to form a supporting surface for a refractory lining which is cast in situ on the door inner face. The flanges are joined together at their edges with one flange being directed toward the other such that the flanges on the faces of the door are spaced apart to

2

form a water jacket or reservoir. Tubes, hollow studs, or other conduit members extend from the door inner face into the lining and hold it in place on the door inner face. The door jacket and tubes are filled with water, and in the known doors, the water is circulated by convection current to and from the jacket through the tubes.

An object of the present invention is to provide a forced circulation water-cooled furnace door having a monolithic refractory lining secured on the door inner face by embedded hollow keys arranged on the door to furnish maximum support for the lining.

Another object is the provision of a water-cooling system for a furnace door having hollow elements which support a refractory lining on the door and which are designed to conduct water under pressure through the system to achieve maximum cooling efficiency.

A forced circulation water-cooled furnace door illustrating certain features of the present invention may include a door having a water chamber and refractory lining as above-described and having door reinforcing hollow keys which are embedded within the refractory lining. The keys are connected to a water inlet for receiving water under pressure, and empty into the door water chamber from which the water is exhausted through an outlet passing through an inner face flange.

A complete understanding of the invention may be had from the following detailed description of a specific embodiment thereof when read in conjunction with the appended drawings, wherein:

FIG. 1 is an elevational view of the door inner face without the refractory lining applied thereto;

FIG. 2 is a longitudinal cross-section of the door taken along the vertical centerline II—II of FIG. 1, with refractory material in place on the door inner face;

FIG. 3 is an enlarged fragmentary cross-sectional view of the door taken along line III—III of FIG. 1 which illustrates the connection of a transverse hollow rib with a channel;

FIG. 4 depicts in an enlarged fragmentary cross-sectional view taken along line IV—IV of FIG. 1 a connection between a vertically extending hollow rib and a water chamber; and

FIG. 5 shows the coupling of an inlet pipe and a channel in a cross-sectional view taken along line V—V of FIG. 1.

Referring to the drawings, wherein like reference characters designate like or corresponding parts throughout the several views, there is shown in FIGS. 1 and 2 a furnace door generally designated number 11. An outer door face 12 of heat resistant metal, for example, has its marginal portions 13 turned rearwardly to form a continuous peripheral flange 14. Laterally spaced from the outer face 12 and in parallel relationship therewith is a door inner face 15 having its marginal portion 16 directed rearwardly, inwardly, and then outwardly to form a flange 17.

As best shown in FIG. 2, the parallel spacing of the faces and their flanges defines the formation of a water jacket 18 within which are arranged transverse channels 19 having their edges sealed fixedly to the door inner face 15. The channels 19 are of sufficient length to extend or to overhang the water jacket flange portion 21, FIG. 5, and are each connected to a water inlet pipe 22 located in the portion 21 by a conduit 23. A duplicate

water pipe 22 is located in the jacket portion 21 on the left side of the door as viewed in FIG. 1; as circumstances dictate, the water may be introduced into the door from either one or both of the pipes 22. The lower end 24 of each pipe 22 is restricted in diameter and open such that cool water may be forced directly toward the bottom of the door 11. At the same time, water is fed through the conduits 23 to transverse channels 19 without an appreciable loss of water pressure in the channels 19 caused by the feeding of water through the open end 24 of the pipe 22. Clean-out plugs 25 are located in the lowermost corners 26 of the door 11.

Keys or ribs 27 are positioned on the door inner face 15 and are joined at their ends 28 to the flange 17 of the inner face 15. The keys or ribs 27 are trapezoidal in cross-section, FIG. 4, and extend across the inner face 15 from the inner flange 17 at one location to the inner flange 17 at an opposed location, as shown in FIG. 1. Similar keys or ribs 29 are arranged between the two substantially transverse ribs 27, and between the upper transverse rib and the inner flange 17. Both ribs 29 are closed at their upper and lower ends 31 by their rigid connection with the flange 17 and with the ribs 27.

The small structural channels 19 communicate with the two transverse ribs 27 via apertures 32 passed through the inner face or plate 15, and the ribs 27, in turn, open into the water jacket flange portion 21 through suitable ports 33 through the inner flange 17. The water jacket 18 is flow-connected to the vertical keys or ribs 29 through vertical slots 34 provided through the inner face 15. Water outlets 35 extend through the door outer flange 17 into the jacket 18.

The transverse ribs 27 are upwardly inclined from their mid-point, for example, toward the flange 17 with the lowermost point being at the juncture of the ribs 27 with the structural channels 19. The recess 36 between the door inner flange 17 is filled with a refractory material 37, which is cast in situ and hardened within the recess. As shown best in FIG. 5, the inner flange 17 overhangs the material 37 at its periphery which contacts the flange, thus supporting the lining 38 within the recess in some measure.

The hollow keys 27 and 29 provide the maximum support of the lining 38 onto the inner face 15 within the recess 36 by virtue of the trapezoidal cross-section of the keys and their special arrangement on the inner face. The upwardly extending transverse keys 27 sustain the lining 38 on the inner face 15, and combined with the vertical keys 29, maintain the lining rigidly on the door. The keys are embedded within the material 37 as the lining is cast in place.

As is conventional with open-hearth furnace doors, lifting lugs 39 are provided on the upper surface of the door, and a furnace inspection opening 41 and lining inspection ports 42 are standard features.

Having described the preferred embodiment of the invention, its operation may be understood readily. Assuming the door 11 is to be placed in position on an active furnace, a water line, not shown, is connected to one of the water pipes 22, the pipe not used being plugged. Water is introduced into the pipe 22, which is connected to a hose and flows under pressure through conduits 23 into the structural channels 19. Water also flows through the pipe open end 24 into the jacket 18 in the flange portion 21 at the bottom section of the door.

From the structural channels 19 the forced circulation water enters the hollow keys 27 through apertures 32 in the inner face 15, and flows through the keys 27 upwardly and transversely toward the marginal flange portion 21 of the jacket 18. The water then is fed through the ports 33 in the flange 17 into the jacket 18. The vertical keys 29 receive water from the jacket 18 and return the water through the same slots 34, and the heated water is forced through the outlet 35 and removed from

the door by suitable connection with a hose or pipe, not shown.

The forced circulation of water through the hollow keys of the door which are embedded in the refractory material 37 of the lining 38 maintains the metal and refractory material of the door at a temperature where the deleterious effects of the furnace heat are reduced, thus prolonging the life of the door. The configuration of the ribs affords maximum support of the refractory lining, and maximum heat exchange between the water and the heated refractory material is also achieved by the large contact area provided between the ribs and the refractory lining.

It is manifest that the above-described embodiment of the invention is merely illustrative and that numerous modifications may be made within the spirit and scope of the invention. Further, it will be understood that the selection of one inlet pipe and one outlet in the circulation system is only an example of one type of arrangement which may be operated upon in practicing the invention, and that the invention is not limited to use with one pipe and one outlet, but that both pipes and outlets may be used in the circulation system simultaneously, or any combination thereof.

What is claimed is:

1. A furnace door comprising an inner plate, an outer plate in spaced parallel relation with the inner plate, marginal flanges extending from the plates and rearwardly turned with the inner plate flange extending for a first portion inwardly and then for a second portion outwardly to join the outer plate flange sealingly, a water jacket defined by the spaced plates and flanges, the inner plate and its flange first portion defining a central recess, hollow keys of trapezoidal cross-section spaced within the recess and sealed to the inner plate and to the inner plate first flange portion, the keys opening at their ends into the jacket between the marginal flanges of the plates, structural channels fixed sealingly to the inner plate and positioned within the jacket, the channels being in communication with the keys via apertures through the inner plate, the keys within the recess being located to anchor a refractory capable of being applied in the recess to cover the inner plate and the keys, a water inlet flow connected to the channels and in communication with the jacket, and a water outlet connected to the outer plate and in communication with the jacket whereby water forced through the inlet flows through the channels and to the jacket simultaneously, from the channels to the keys, and from the keys to the outlet in the sequence named.

2. A furnace door having a top, sides and a bottom comprising spaced inner and outer plates forming between them a water jacket, the plates having inwardly-turned flange portions joined together to provide a recessed inner face on the door with a hollow marginal flange thereabout, a water inlet pipe extending down said marginal flange at one side of the door toward the bottom and having a restricted discharge terminal at the end thereof spaced from the bottom, a pair of spaced transversely-extending channels welded to the inner plate inside the water jacket, each channel forming a water conduit transversely across the door, a connection for each such conduit to said water inlet pipe, a pair of spaced hollow keys extending transversely across the recessed inner face of the door, each key forming a water conduit that extends continuously across the exposed face of the inner plate, the ends of the hollow keys opening into the hollow flange at each side of the door, one such hollow key being in communication at its center with the conduit provided by one of said channels through a port in the inner plate whereby water from said channel may flow into the hollow key at the center and flow laterally into the flange at each side of the door, the other of said hollow keys being in similar communication with the other of said channels, the door also having a hollow verti-

cal key in the recessed area between the two transversely-extending keys which is in flow communication with the space between the plates throughout substantially its entire length, a similar vertical key between the upper of the said transversely-extending keys and the marginal flange at the top of the door in similar flow communication along its length with the space between the two plates, an outlet connection at the top of the door and a refractory material filling the recess and covering the keys.
